UNITED STATES PATENT OFFICE.

WILLIAM C. STARKEY AND GLENN H. BOLUS, OF MANSFIELD, OHIO, ASSIGNEES TO THE
OHIO BRASS COMPANY, OF MANSFIELD, OHIO, A CORPORATION OF NEW JERSEY.

HANGER FOR TROLLEY WIRES.

1,161,081.

Specification of Letters Patent. Patented Nov. 23, 1915.

Application filed March 21, 1912. Serial No. 685,232.

To all whom it may concern:

Be it known that we, WILLIAM C. STARKEY and GLENN H. BOLUS, citizens of the United States, and residents of Mansfield, in the county of Richland and State of Ohio, have invented certain new and useful Improvements in Hangers for Trolley-Wires, of which the following is a specification.

Our invention relates to suspension devices for electric conductors, and has more particular reference to improvements in trolley wire hangers, of the type generally known as catenary hangers.

The object, primarily of our invention, is to provide a cheap, efficient and durable hanger for catenary systems of suspending trolley wires, which will be exceedingly strong, but light in weight.

A further object is to provide an improved catenary hanger which can be made of two parts, namely, a wire holding member and a suspension member, assembled in operative relation in a simple and efficient manner.

A further object is to provide an improved trolley wire hanger which can be quickly and securely attached to the wire to be suspended, and which, when attached to the wire, will offer no obstruction whatever to the traveling trolley or contact member.

To the attainment of these ends, and the accomplishment of other objects hereinafter appearing, our invention consists in the features of novelty disclosed in the construction, combination and arrangement of parts shown in the accompanying drawings, which illustrate one embodiment of our invention, and in which—

Figure 1 is a view in elevation of our improved hanger attached to a trolley wire. Fig. 2 is an end view of the lower portion thereof, the wire holding member being shown in transverse section; Fig. 3 is a transverse sectional view on line 3—3 of Fig. 1; Fig. 4 is a side elevation of the wire holding member, the suspension member being omitted; Fig. 5 is a similar view of a modified form of wire holding member; Fig. 6 is a view similar to Fig. 1 showing a modified structure embodying our invention; Fig. 7 is an end view thereof; and Fig. 8 is a longitudinal, sectional view thereof on the line 8—8 of Fig. 6.

In the drawings we have shown our invention as embodied in a hanger which is adapted for supporting trolley wires of the so-called grooved and figure 8 types, but it is to be understood that our improved hanger is equally as well adapted to the round or other types of wire.

The hangers or wire suspending devices shown in the drawings each embody a wire holding member A, and a suspension member B is disposed preferably at substantially right angles thereto, and each member thereof is composed preferably of a single piece of metal. The member or ear A has a lower portion 1 in which a groove 2 is formed for the purpose of receiving the trolley wire 3. The shape of this groove varies in accordance with the cross-sectional shape of the wire to be hung. In fact, the groove or channel may be given any desired shape, but we prefer that it conform to that of the wire so that a more accurate connection may be made and then soldered therein if desired. The edges or lips 4 are preferably made bendable so that they can be hammered or pressed inwardly to embrace the wire, and when used with the grooved or figure 8 wire, the bendable lips are made of such thickness that when they are forced or bent into the grooves 5 of the wires as shown in Fig. 3, they lie within the general confines of the wire and do not noticeably increase the size of the wire at these points. For the sake of lightness in weight, without sacrifice to strength, we make the portion 1 of substantially uniform thickness, and provide thereon one or two integral members or flanges 6 depending on the particular requirements to which the hanger is to be adapted. These upstanding members 6 constitute means to which the suspension member B may be attached, and if desired they may be formed as a single short lug or lugs as the case may be. If the wire holding member A is made of the so-called extruded brass which is, as well known, formed by forcing brass in a heated viscous state under high pressure through a die (and it is preferably so made), the flanges or members 6 extend the length of the lower or wire-holding portion 1. These members or flanges 6 also serve as strengthening ribs against bending strains. In Figs. 1, 4 and 6 we have shown the flanges

as tapered toward the outer ends for the sake of appearance as well as lightness in weight. However, they may be of uniform height from end to end just as the members A come 5 from the die (see Fig. 5). Thus, as is obvious, the metal may come from the die in a continuous length and simply cut up into short lengths which form the members A.

The suspension member B may be of any 10 suitable shape and construction, but we prefer that it be made of a single piece 8 of strap metal having its upper end formed for attachment to the messenger wire. This permits the straps 8 to be cut from long 15 lengths of stock strap metal and a great saving in manufacturing expenses is accomplished. Figs. 1, 6, 7 and 8 show a method of forming the upper ends of the strap 8 for attachment to a messenger wire. 20 As shown the upper portion thereof may be doubled back upon itself to form a long loop 15, and the end 14 may be turned laterally to close the lower end of the loop and prevent the hanger from becoming accidentally unhooked from the messenger. 25

As before intimated, the number of flanges 6 depends to some extent upon the manner in which the suspension member B is to be attached to the wire-holding member A. For instance, one flange or rib 30 6 may be formed on the member A and the lower end of the suspension strap may be doubled back on itself or bent to form an eye, loop or hook 9. This may be hooked 35 into a slot or spring 10 in the flange or rib 6 (Figs. 1, 2, 4 and 5) and the end portion 11 and the adjacent metal 12 may be jammed together or offset to close the hook and position the suspension strap in substantially 40 central alinement with the member A. It is seen, however, by reference to Figs. 6, 7 and 8, that if desired the member A may be provided with two parallel flanges 6 spaced apart to form a slot or channel into which 45 the squared lower end 16 of the suspension strap may be placed, and a rivet or bolt 17 passed through suitable holes in the flanges and strap to bind the parts together.

It is thus seen that our improved hanger 50 possesses the combined advantages of simplicity, durability, cheapness in manufacture and neatness in appearance.

What we claim is:

1. A catenary hanger comprising a metal 55 strap formed with a flat hook, the extremity of the strap being bent edgewise and then at right angles to close the hook forming a flat loop in which a messenger wire fits loosely to permit the hanger to rise and fall 60 with respect to a messenger wire.

2. A catenary hanger comprising a flat metal strap bent over at one end to form a flat hook, the extremity being bent edgewise and then at right angles at a distance

from the hook to form a closed loop which 65 may be hooked over a supporting wire without bending the metal strap.

3. A catenary hanger consisting of a metal strap having means at one end for attachment to a trolley wire, the other end 70 being bent over to form a flat hook in which a messenger wire is movable, the extremity of the hook being bent edgewise and then at right angles to close the hook and to form a loop adapting the strap to be hooked over 75 a messenger wire to engage the messenger wire in the loop and to prevent the messenger wire from disengagement when the hanger is attached to a trolley wire which is parallel to a messenger wire which supports it.

4. A catenary hanger for trolley wires consisting of a flat metal strap provided at one end with means for attachment to a trolley wire, the other end being bent to 80 form a flat hook, the extremity of the end being bent edgewise and then at right angles, the right angled portion being spaced 85 a distance from the hook forming a closed loop into which a suspension wire may be 90 inserted by placing the said right angled portion over the wire and parallel thereto and then rotating the strap to engage the wire in the hook.

5. A two-piece catenary hanger consisting 95 of a member having loops for attachment to a trolley wire and a metal strap secured at one end to the member having a flat hook at the other end bent edgewise at the extremity and then at right angles thereto to 100 form a loop into which the messenger wire may be inserted without attachment thereto permitting the hanger to rise and fall with respect to the messenger wire but preventing disengagement of the hook from the messenger wire when the hanger is attached to a trolley wire parallel thereto.

6. A catenary hanger for trolley wires comprising an elongated piece of extruded metal formed for attachment to a wire and 110 having an integral upstanding flange extending longitudinally thereof provided with a slot therein, and a flat metal strap disposed at right angles to the longitudinal axis of said other piece having one of its 115 ends passed through the slot and doubled back upon itself and having its other end formed with a hook, the extremity of which is offset therefrom to form a closed loop 120 into which a messenger wire may be freely inserted to permit the hanger to rise and fall with respect to the messenger wire but preventing its disengagement therefrom.

7. In a catenary hanger, a member adapted to be rigidly secured to a trolley wire, 125 and a flat metal strap fixed at one end to the member and formed at the other end with a flat hook, the extremity of which is offset

to form a loop which may be hooked over a messenger wire by rotating the hanger with respect to the messenger wire and preventing the disengagement by a right angled movement with respect to the messenger wire.

In testimony whereof we have signed our names to this specification, in the presence

of two subscribing witnesses, on this 18th day of March A. D. 1912.

WILLIAM C. STARKEY.
GLENN H. BOLUS.
